UNITED STATES PATENT OFFICE.

FREDERIC HENRY TREVELLIAN, OF WELLINGTON, NEW ZEALAND.

CASH-REGISTER.

955,016.

Specification of Letters Patent. Patented Apr. 12, 1910.

Application filed November 3, 1908. Serial No. 460,946.

To all whom it may concern:

Be it known that I, FREDERIC HENRY TREVELLIAN, a subject of His Majesty the King of Great Britain and Ireland, residing at 5 256 Lambton Quay, Wellington, in the Provincial District of Wellington, in the Dominion of New Zealand, have invented certain new and useful Improvements in Cash-Registers, of which the following is a 10 specification.

This invention relates to cash registers having bands of paper whereon invoices and the like are to be written and copies thereof taken.

15 By this invention is provided mechanism whereby two or more assistants may use one machine, a separate paper band being provided for each assistant whereon to summarize the totals of his invoices. A separate 20 cash drawer is also provided for each assistant.

The invention is illustrated in the accompanying drawings wherein:—

Figure 1, is a plan of the register, Fig. 25 2, a plan with the lid of the casing removed, Fig. 3, is a sectional elevation on line A—A Fig. 2, Fig. 4, is a sectional elevation on line B—B Fig. 2, Fig. 5, a similar view with the upper cash drawer released, Fig. 6, is a cross 30 sectional elevation on line C—C Fig. 2, Fig. 7, is a reverse sectional elevation, with the side of the casing removed, and Fig. 8, a plan of a register with one cash drawer, Figs. 9 and 10, are sectional elevations of 35 spring operated bearings, Fig. 11, is a perspective view of two keys, Fig. 12, an inverted plan of a spring catch for holding the lid of the casing open, Fig. 13, a perspective view of locking plates and levers, Fig. 14, a perspective view of a lever, Fig. 40 15, a perspective view of a locking plate, Fig. 16, a perspective view of clips and associated parts, Fig. 17, a perspective view of clips, Fig. 18, a sectional elevation of a 45 spring operated socket for adjusting paper bands, and Fig. 19, a sectional elevation of a spring socket for operating a summarizing band independently of an invoice band, Fig. 20, is an elevation of bell and mechanism.

50 The mechanism is contained within a metal casing (1), having a lid (2) hinged at (3) to the casing, and comprises longitudinal frame plates (4) and (5) connected together by cross bars (7) and (8) by a plate (9) secured to the said plates by screws (10), the said frame plates being pivoted by

pins (11) in eye sockets (12) fixed to brackets (13) integral with the rear of the casing (1). The pins (11) pass through the frame plates and screw into a shaft (15) whereon 60 is mounted a roller (16). Rollers (17) and (18) are journaled at one-end upon bearings consisting of conical ended studs (19) screwed into the frame plate (4) and at the other end upon spring operated conical ended studs (20) (see Fig. 9) slidable in sockets (21) integral with the frame plate (5) and having stems (23) projecting through the ends of the sockets and furnished with heads (24) upon the exterior of 70 the sockets. Springs (25) in compression within the sockets tend to project the studs and bring them into close contact with the rollers (17) and (18), whereby friction is set up sufficient to prevent the rollers from 75 overrunning. The rollers can be readily removed by withdrawing the studs 20.

Bands of paper 27 and 28 rolled upon the rollers 17 and 18 respectively pass over the roller 16 mounted upon the shaft 15 as previously described. The band 27 after leaving the roller 17 passes beneath a sheet of carbon paper 30 and over the plate 9; and the band 28 passes over the said sheet of carbon paper below an opening 31 in the 85 lid 2. The portion of the paper exposed in the opening is available for the purpose of writing an invoice or the like thereon. The bands then pass beneath a tension roller 32 the band 28 passing upward through a guide 90 33 (see Figs. 2, 3, 7 and 8) consisting of a hood 34 fixed at each end to brackets 35 and 36 and covering the top of the roller 32 and having a knife edge 37, and of a director 38 curved to guide the paper upward and fixed 95 at its ends to the hood 34. The band 27 passes below an opening 39 closed by a sheet of glass 40 through which it is exposed to view, and thence around a roller 41 and is finally coiled upon a receiving roller 42. 100

The bands of paper are advanced by an operating handle 43 (see Fig. 2) upon a shaft 44 journaled in the plates 4 and 5, and has secured upon it a spur wheel 45 gearing with a second spur wheel 46 mounted freely 105 upon a shaft 47 also journaled in the plates 4 and 5. The wheel 45 is prevented from being turned, in a direction reverse of that shown by the arrow, by a pawl 49 engaging with the teeth of the wheel. The shaft 47 110 has secured upon it a finely fluted roller 50 (see Fig. 3) located between the rollers 32

and 42. The roller 42 is secured upon a shaft 51 having projecting ends guided in slots 52 formed in the plates 4 and 5, and supported upon arms 53 pivoted upon the cross bar 7 and a spring 54 normally raises the arms and forces the roller 42 against the roller 50. The tension roller 32 is mounted in brackets 35 and 36 pivoted by pins 56 to the outside of plates 4 and 5 (see Fig. 7). The other ends of the brackets are provided with screws 57, the heads of which bear against the under side of plates 58 and 59 pivoted to brackets 60 integral with the plates 4 and 5. By adjusting the screws 57 the brackets 35 and 36 are raised or lowered to make the roller 32 bear more or less heavily on the roller 50. The paper being gripped between the rollers 32 and 50 and between the rollers 50 and 42 the revolution of the roller 50 causes the paper to be unrolled from the rollers 17 and 18 and the band 27 to be rolled upon the roller 42 and as the diameter of the paper rolled upon the said roller 42 increases the arms 53 yield against the pressure of the spring 54 and allow the shaft 51 to descend in the slots 52.

The handle 43 is prevented from turning more than one single revolution at a time by a cam 62 secured to the shaft 44 and contacting with a tumbler plate 63 herein-after to be described.

Referring now more particularly to Figs. 2, 4, 5, 6, 13, 14, and 15. The mechanism employed for advancing the bands of paper for summarizing totals of invoices consists of a frame comprising plates 64 and 65 united together by bars 66 and 67 and by plates 68 and 69 secured to the said plates by screws 70. The frames have slots 71 which receive lugs 72 integral with the front of the casing and support the front of the frame. The rear of the frame is supported by lugs 73 projecting from the plates 64 and 65 and resting upon the brackets 13. Screws 74 passing through the lugs 73 screw into the brackets 13. Rollers 76 and 77 are pivoted at one end on studs 78 and 79 screwed through the plate 65 and having conical ends 80 and 81 and at the other end on spring operated conical studs 82 and 83 similar to the studs 20 hereinbefore described. Bands of paper 84 and 85 are rolled upon the rollers 76 and 77 and pass over the plates 68 and 69 and over end rollers 86 and 87 and thence to rollers 88 and 89 respectively mounted in spring operated conical bearings 90 and 91, one of which is shown on a large scale in Fig. 10. The stems 92 are fixed to the conical bearings and slideable in sockets 21 integral with the frame plate. Thimbles 93 having integral ratchet wheels 94 and 95 are mounted upon the sockets 21. The conical bearings 90 and 91 are provided with lugs 96 which em-

gage slots formed in the rollers 88 and 89. Narrow openings 97 and 98 (see Fig. 1) are provided in the lid 2 above the plates 68 and 69 exposing sufficient paper for writing thereon the total of one invoice at a time only.

Upon the frame plate 64 and pivoted at or near their centers are levers 100 and 101 having at their upper ends pivoted pawls 102 and 103 engaging the ratchet wheels 94 and 95. A stop 104 limits the movement of the lever 100 in one direction, and a stop 105 similarly limits the movement of the lever 101. A pin 106 projecting laterally from both sides of the lower end of lever 100 engages slots 107 and 108 in the ends of locking plates 109 and 110 disposed side by side and corresponding in shape. A pin 111 projecting laterally from one side of the lower end of the lever 101 engages a slot 112 in the locking plate 110. The locking plates 109 and 110 extend to and rest on the ends of rocking levers 113 and 114 pivoted side by side at or near their centers upon a pin 116 projecting from the frame plate 64, said levers being pivotally connected to vertical spindles 117 and 118 slideable in lugs 119 and 120 integral with the rear of the casing. The ends of the spindles are beveled and adapted to pass into holes in brackets 121 and 122 fixed to the back of superposed cash drawers 123 and 124. Springs 125 and 126 located on the spindles 117 and 118 and in compression between the lug 119 and pins 128 and 129 projecting from the spindles 100 tend to project the spindles downward. Spiral springs 130 and 131 in compression between the drawers 123 and 124 and the rear of the casing to which they are fixed, project the drawers outward when released by the rising of the spindles 117 and 118. Interposed between the locking plates 109 and 110 is the tumbler plate 63 which has projecting pins 133 slideable in slots 134 formed in the frame plate 64. A jaw consisting of two side springs 135 and 136 is provided to keep the tumbler plate 63 from accidentally becoming displaced. Lateral projections 137 and 138 on the plates 109 and 110 are adapted to bear against the front of the plate 63. Keys 140 and 141 (see Fig. 11) have cranks 142 and 143 and shanks 144 and 145 adapted to engage holes 146 and 147 in the tops of the levers 100 and 101. L shaped slots 149 and 150 (see Fig. 1) are provided in the lid 2, the transverse portion of the slot 149 being longer than the corresponding part of the slot 150. The holes 146 and 147 fall immediately below the inner extremity of the slots 149 and 150, the perpendicular portions of the said slots extending from the other extremities of the transverse portions. The cranks 142 and 143 of the keys 140 and 141 have lengths corresponding to the lengths of the trans-

verse portions of the slots 149 and 150 so that the key of one assistant will not open the drawer or operate the invoice band of the other assistant.

- 5 The machine is operated in the following manner:—After an invoice has been made out, for example on the band 28 and the total of the invoice written upon the summarizing band 85 by the assistant controlling the upper cash drawer 123, the key 141 engaging the lever 101 is pulled forward and assumes the position shown in Fig. 5. The pawl 103 on the lever 101 rotates the ratchet wheel 95 and the roller 89 about one-eighth of a revolution, the paper band 85 being thus advanced a short distance to allow for the next entry of an invoice total. The lever 101 has also advanced the locking plate 110 by its pin 111, the advance being limited by a stop 152 integral with the frame plate 64 and the projection 138 on the plate 110 carries backward the tumbler plate 63 to the position shown in Fig. 5 leaving the cam 62 free to rotate. The handle 43 can now be operated and the cam 62 during its rotation contacts with the shoulder 153 of plate 109 which is depressed and the spindle 117 raised through the intervention of the lever 113 and the cash drawer 123 released. 10 The cam continuing its rotation strikes the shoulder 154 of the tumbler plate 63 which is carried forward to its original position (see Fig. 4), and the cam again comes to rest upon the plate 63. The locking plate 110 and lever 101 have also been returned to their original positions by the plate 63 contacting with the projection 138. The cash drawer may then be returned to its position to be retained by the spindle 117. 15 The machine is thus prevented from again being operated until one of the keys 140 or 141 is brought into use.

When the assistant controlling the drawer 124 desires to operate the machine he introduces his key 140 through the slot 149 into the top of the lever 100. By pulling the key forward the pawl 102 rotates the ratchet wheel 94 and roller 88 about one eighth of a revolution, the summarizing paper band 84 being thus advanced a short distance for the next entry of an invoice total. The lever 100 has also advanced the locking plate 109 by its pin 106, the advance being limited by the stop 152 and the projection 137 on the plate 109 carries backward the tumbler plate 63 leaving the cam free to rotate. In this instance the locking plate 110 is not advanced, the pin 106 merely sliding in the slot 108 of this said plate, the slot 108 being longer than the slot 107. The handle 43 can now be operated and the cam 62 during its rotation contacts with the shoulder 153 of the plate 110 which is depressed and the spindle 118 raised through the intervention of the rocking lever 114, and the cash drawer

124 released. The remaining operations are the same as those described in reference to the plate 109.

The effect of the operation of the lever 101 by the first assistant is to advance the locking plate 110 to a position where it cannot be depressed by the cam 62 for the purpose of releasing the lower drawer 124 which is under the control of the second assistant, and similarly the effect of the operation of the lever 100 by the second assistant is to advance the plate 109 to a position where it cannot be depressed for the purpose of releasing the upper drawer 123 which is under the control of the first assistant.

The lid 2 may be held open by means of a spring operated catch shown in Figs. 1 and 12 and comprises a catch 157 pivoted to the lid 2 by a pin 158 and engages a slot 159 in one side of the casing 1. A coil spring 160 is in compression between the catch and snib 161 on the lid. The catch is brought out of engagement with the casing by means of the handle 162.

Warning that the machine has been operated is given by bells 163 (see Fig. 6) fixed to the back of the casing by stems 164. Hammers 165 pivoted upon the back of the casing are operated by pawls 166 and 167 which are pivoted to the vertical spindles 117 and 118 by the pins 128 and 129 and engage the tails of the hammers. Coil springs 169 normally keep the hammers in engagement with the pawls. When the spindle 117 and 118 is raised the pawl 166 or 167 lowers one of the hammers 165 and when the said spindle is released the spring 169 raises the hammer to strike the bell. The bells may be of different tones so that it will be known which drawer has been opened.

If the invoice heading on the band 28 should accidentally get out of correspondence with the opening 31 it can be easily adjusted to its proper position by means of a socket 170 (see Figs. 2, and 18) having a milled head 171 and slidably mounted on the shaft 47 by means of a screw 172 upon the socket and projecting into a groove 173 formed in the shaft 47. A screw 174 screwed into the end of the shaft 47 has a head 175, and a coil spring 176 located upon the said screw 174 is in compression between the head 175 and a shoulder 177 formed upon the interior of the socket. The wheel 46 is mounted freely upon the shaft 47 has a sleeve 178 provided at its end with teeth 179. The spring 176 normally keeps teeth 180 formed upon the end of the socket 170 in engagement with the teeth 179. By drawing the socket out of engagement with the teeth, the roller 50 can be rotated independently of the handle 43 by means of the milled head 171, and the paper band adjusted to the required position.

A holder for retaining sheets of carbon

paper is illustrated in Figs. 2, 3, 6, 16, and 17, and in the case of a single sheet of carbon paper the holder comprises a grooved bar 182 extending from the frame plate 4 to the frame plate 5 to which it is pivoted by ears 183 upon pins 184. A wire spring 185 lying within the groove of the bar 182 is bent at one end to form a hook 186 which engages a pin 187 traversing the said groove. 10 The other end of the wire is formed into a loop 188 and has its end 189 engaged in a hole formed in the holder. The loop forms a spring which permits the end 189 to be withdrawn from its hole. The holder is 15 pivoted as described for the purpose of readily placing the band 27 in position.

In the case of a third band of paper 190 (see Fig. 16) being employed with the bands 27 and 28 for the purpose of making a second carbon copy of an invoice, the carbon 20 paper holder is made with two grooved bars 191 and 192, both pivoted to the frame plates 4 and 5 by their ears 193, 194, 195 and 196, upon the pins 184, the band 190 passing 25 through the space between the bars 191 and 192. Wire springs 197 and 198 lying within the grooves of the bars are bent to form hooks 199 and 200, which engage pins 201 and 202 traversing the said grooves. The 30 other ends of the wires are formed into loops 203 and 204 and at this end are retained by hooks 205 and 206 pivoted upon screws 207 and 208 to the holder. The sheet of carbon paper 30 lies between the bands 28 and 27 35 and the carbon paper 209 lies between the bands 190 and 28, and are held at one end within the grooves of the bars 191 and 192 by the wire spring. The sheets of the carbon paper may be renewed by releasing the 40 wire springs and substituting fresh sheets.

Referring now to Fig. 19 which shows a spring socket 210 whereby a summarizing band may be advanced without advancing an invoice band. This socket is employed on 45 registers which are intended to be used in connection with a small business by an employer alone, who can enter small sales on the summarizing band without making out an invoice. The wheel 46 and its sleeve 178 are mounted freely on the axle 47, and the teeth 180 of the socket are adapted to engage the corresponding teeth 179 formed on the sleeve 178 as previously described. In 50 this case however the spring 211 normally keeps the two sets of teeth out of engagement by bearing against the sleeve and against a shoulder 212 formed in the socket 210. The teeth may be retained in engagement by means of a spring catch 213 lying 55 in a groove 214 formed in the axle 47. When the socket is advanced to bring the teeth into engagement, the catch 213 rises out of its groove and engages the face of the socket, thereby preventing the disengagement of 60 the teeth until the catch is depressed. The

outward movement of the socket is limited by a cap 215, the rim 216 preventing the operator's finger being trapped when the socket recedes under the influence of the spring 211 after the catch 213 has been depressed by the finger.

When an operator wishes to advance the summarizing band and open the drawer without advancing the invoice band, he depresses the catch 213 to throw the teeth out 75 of engagement. If the handle 43 is then turned the summarizing band will be advanced and the invoice band remain stationary. When however the operator desires to advance both the summarizing band and 80 the invoice band, he pushes the socket 210 until the catch 213 rises and retains the socket. A screw 217 passing through the socket has its end slidable in a groove 218 formed in the axle 47. The movement of 85 the wheel 46 is communicated through the socket and screw 217 to the axle.

Referring now to Figs. 7 and 8 which show a register which contains only one cash drawer 219 and one summarizing paper 90 band 220. A lever 221 is pivoted to the side of the frame plate 222 on a pin 223 and has pivoted upon it a pawl 224 which engages a ratchet wheel 225 to advance the paper bands 220. At its lower end the lever 221 is 95 bifurcated and pivoted to a locking plate 226, the end of which has a jaw 227 adapted to engage a projection 228 integral with the side of the frame plate 222, the lower member 229 of the jaw being longer than the 100 upper member 230. The other end of the plate 226 is continued back and engages a pin 231 on a vertical spindle 232 which normally holds the cash drawer closed. The locking plate 226 has a member 233 where- 105 with the cam 234 contacts, and is prevented from being rotated. Upon the lever 221 being operated by its key 235, the paper band 220 is advanced, and the locking plate 226 brought out of engagement with the 110 projections 228. The member 233 is with- 115 drawn from contact with the cam 234, which is then free to be rotated. During its rotation, the cam depresses the plate to the position shown in dotted lines in Fig. 7. The 115 rear end of the plate raises the spindle 232 and the drawer 219 is released. The cam during the continuation of its rotation al- 120 lows the locking plate 226 to rise under the action of a tension spring 237 until the lower 120 member 229 of the jaw 227 meets the pro- 125 jection 228. The cam next contacts with the shoulder 238 of the locking plate 226 and returns the plate to its forward position and into engagement with the projection 228.

Figs. 8 and 20, show a modification of bell mechanism, the bell 240 is mounted upon a stud 241 fixed to the casing 1, and the ham- 130 mer 242 is pivoted upon a stud 243 also fixed to the casing. A cam 244 secured to the

shaft 44 raises the hammer when the handle 43 is operated. After the hammer has been released by the cam, the spring 245 causes the hammer to strike the bell. The lid of 5 the casing is locked by means of a lock 246 and a key 247.

What I do claim and desire to secure by Letters Patent of the United States is:—

1. In cash registers the combination of 10 rollers holding invoice and summarizing bands, a receiving roller upon which said bands are wound, means for shifting said summarizing and invoice bands and means for adjusting said receiving roll as the bands 15 unwind from one set of rollers and wind on the other set as set forth.
2. In a cash register of the kind described, the combination with rollers whereon paper bands are rolled, of an operating handle, a 20 shaft to which the handle is secured, a cam fixed to the shaft, locking plates and a tumbler plate operable together with the cam, means for operating the plates to release the cam, spring operated cash drawers 25 and means for releasing the cash drawers, as set forth.
3. In a cash register of the kind described, the combination with rollers whereon paper bands are rolled, of an operating handle, a 30 shaft to which the handle is secured, a cam fixed to the shaft, locking plates and a tumbler plate operable together with the cam, summarizing paper bands, rollers upon which the summarizing bands are wound, 35 levers for advancing one or other of the locking plates, spring operated cash drawers and means for releasing the cash drawers, as set forth.
4. In a cash register of the kind described, 40 the combination with rollers whereon paper bands are rolled, of an operating handle, a shaft to which the handle is secured, a cam fixed to the shaft, locking plates and a tumbler plate operable together with the cam, summarizing paper bands, rollers upon 45 which the summarizing bands are wound, levers for advancing one or other of the locking plates, ratchet wheels connected to the rollers of the summarizing bands, pawls 50 pivoted to the levers and engaging the teeth of the ratchet wheels, and means for operating the levers as set forth.
5. In a cash register of the class described, 55 a cranked key adapted to pass through an L shaped slot, a lever below the slot having a hole to receive the end of the key, as set forth.
6. In a cash register of the class described, 60 locking plates disposed side by side, a tumbler plate lying between the locking plates, a cam locked by the plates, and means for operating the plates independently, as set forth.
7. In a cash register of the kind described, 65 locking plates disposed side by side, a tum-

bler plate lying between the locking plates, a cam locked by the plates, levers separating the locking plates, rocking levers operable by the locking plates, spring operated spindles connected to the rocking levers, and 70 cash drawers retained by the spindles, as set forth.

8. In a cash register of the class described, a frame plate, locking plates disposed side by side, a tumbler plate lying between the 75 locking plates and having pins slidable in slots formed in the frame plate, and projections on the locking plates adapted to bear against the tumbler plate, as set forth.

9. In combination in cash registers, a cas- 80 ing, lugs integral with the back of said cas- ing, spindles mounted on said lugs, springs surrounding said spindles, pins pivotally mounted upon said spindles, spring held pivoted hammers provided with lugs en- 85 gaged by said pins, summarizing and in- voice slips and gongs mounted on said cas- ing near its hammers, said elements being put into operation by the shifting of either slip. 90

10. In a cash register of the kind de- 95 scribed, frame plates, a grooved bar pivoted to the frame plates, a wire spring lying in the groove of the bar, a pin traversing the said groove and around which the end of 95 the wire spring is bent, a catch retaining the other end of the wire spring, said wire spring holding a sheet of carbon paper in said groove substantially as set forth.

11. In a cash register of the kind de- 100 scribed, frame plates, grooved bars having integral ears, pins upon which the ears are pivoted to the frame plates, means for se- 105 curing sheets of carbon to the bars there being a space between the bars for the pas- sage of the paper band, as set forth.

12. In a cash register of the kind de- 110 scribed, a shaft, a wheel having a sleeve and mounted freely on the shaft, teeth on the end of the sleeve, a socket slidable on the 110 shaft and having end teeth, a screw through the socket engaging a groove in the shaft, and a spring normally retaining the teeth in engagement, as set forth.

13. In a cash register of the kind de- 115 scribed, a shaft, a wheel having a sleeve and mounted freely on the shaft, teeth on the end of the sleeve, a socket slidable on the shaft and having end teeth, a screw through the 120 socket engaging a groove in the shaft, and a spring normally separating the teeth of the sleeve from the teeth of the socket, as set forth.

14. In a cash register of the kind de- 125 scribed, a shaft, a wheel having a sleeve and mounted freely on the shaft, teeth on the end of the sleeve, a socket slidable on the shaft and having end teeth, a screw through the 125 socket engaging a groove in the shaft, and a spring normally separating the teeth 130

of the sleeve from the teeth of the socket and a spring catch lying in a groove in the shaft, as set forth.

15. In a cash register of the kind described, a shaft, a wheel having a sleeve and mounted freely on the shaft, teeth on the end of the sleeve, a socket slidable on the shaft and having end teeth, a screw through the socket engaging a groove in the shaft, and a spring normally separating the teeth of the sleeve from the teeth of the socket, and a spring catch lying in a groove in the shaft, a cap upon the end of the shaft and having a slotted rim, as set forth.
- 15 16. In a cash register of the kind described, a conical bearing, a stem fixed to the conical bearing, a thimble integral with

the stem, a socket upon which the thimble is mounted, and a toothed wheel integral with the thimble, as set forth.

20

17. In a cash register of the kind described, a frame plate, locking plates disposed side by side, a tumbler plate lying between the locking plates and having pins slidable in slots formed in the frame plate, and a spring jaw secured to the frame plate and retaining the tumbler plate, as set forth.

25

In testimony whereof I have signed my name to this specification in the presence of two witnesses.

FREDERIC HENRY TREVERIAN.

Witnesses:

ERNEST SMITH BALDWIN,
JOHN JOSEPH WATSON.
